UNITED STATES PATENT OFFICE.

ADOLPH RADO AND ADELAIDE D. W. RADO, OF EAST ORANGE, NEW JERSEY.

DUST-MOP CLEANER.

Application filed April 6, 1927. Serial No. 181,392.

Our invention relates to dust mop cleaners and the same is intended to perform the same functions as the device shown in our U. S. Patent No. 1,614,968. The object of the present invention is to provide a dust mop cleaner by means of which the dry or dust mops generally used for dusting floors, may be cleaned in such manner that the dust will be collected within a receptacle. The present method of dusting floors is to pass a dry or dust mop over the floor and when the mop has collected considerable dust, usually the mop is shaken out of the window of the house or apartment, which is an objectionable feature of the method. Furthermore, it is necessary to pass back and forth from the place where the mop is used to the place where it is to be cleaned, a number of times. The present invention comprises a receptacle having a suitable cover, and contained within the receptacle is a foraminous cage, preferably formed of a plurality of wires, within which the head of the mop is adapted to be moved to beat the dust therefrom and to deposit it in the receptacle. The present device is adapted to be used within the house or apartment and it may be readily emptied after an accumulation of dirt after the same has been used a number of times. One object of the present invention is to provide a very simple device for the above purpose, which may be readily attached to or detached from a pail or bucket, so that the latter may be used as a water pail or for any other purpose when not being used as a dust mop cleaner. Another object is to eliminate special construction of the pail itself. Another object is to make the cover readily detachable from the pail, so that the collected dust may be readily discharged from the pail. Another object is to reduce the cost of construction and otherwise simplify the device.

In the drawings forming part of this application,

Figure 1 is an elevation of a dust mop cleaner embodying our invention, showing the mop in position for cleaning, a part of the pail being broken away to show the interior construction,

Figure 2 is a plan view of the cover and basket with a portion of the hinged or movable cover broken away to show the interior,

Figure 3 is a sectional view taken on the line 3—3 of Figure 2, and

Figure 4 is a sectional view taken on the line 4—4 of Figure 2.

The receptacle 1 may be an ordinary pail or a bucket such as is used for general household purposes. Preferably, the pail is provided near its top with a bead or indentation 2 which may be used as a support on which the top or plate 3 may rest. In addition, the wall of the pail is provided with small apertures 4 adjacent this bead which apertures are adapted to receive the locking members on the top plate, as will be set forth.

The plate 3 will, of course, be circular if it is to be applied to a circular pail, and its diameter will conform closely to the diameter at the top of the pail, so that this plate 70 may be inserted from the top and be allowed to rest on the bead 2 to form a top closure for the pail. We have provided sliding latches here shown as wires 5 bent to form handle portions 6 and the opposite ends 7 of 75 these wires are arranged to slide between the top surface of the plate 3 and the straps 8 attached to the plate. We have shown one of these latches at each side of the plate 3 and one end of each latch is adapted to be 80 projected beyond the periphery of the plate 3 for the purpose of extending each through one of the apertures 4 in the upper part of the pail. The stationary cover 3 is provided with a preferably circular opening 9 which 85 is adapted to be closed by means of a hinged cover, preferably made in two sections. For this purpose we have shown a section 10 attached to the stationary plate 3 by means of hinges 11 adjacent the edge of the opening 90 9, and this cover member is shown of sufficient size to cover one-half of said opening. There is a similar cover member 12 connected by hinges 13 with the stationary plate 3 adjacent the edge of the opening 9, and this 95 cover member is adapted to close the other half of said opening. The cover sections at their opposing or adjacent edges are provided with semi-circular recesses 14 which, when the cover members are closed, provide 100 the central apertures through which the mop handle is adapted to project. We have shown handles 15 on the cover sections by means of which the covers may be grasped for opening and closing them.

There is a foraminous cage within which the head of the mop is adapted to be revolved for beating the dust from it, and this we have shown as composed of a series of wires 16 united to form a basket suspended from the 110 stationary plate 3. While this basket may be formed in various ways, we have

shown it composed of a series of vertical wires 16 spaced apart and arranged in a circular form. The upper ends of these wires are encircled by a wire band 17 and the whole is soldered or otherwise connected with the stationary plate 3 adjacent the circular aperture 9. There are horizontally disposed wires 18 extending at right angles to other wires 19 and arranged at the lower ends of the wires 16 to form the bottom of the cage.

To assemble the device the plate 3 which carries the basket is simply inserted into the top of the pail and allowed to move downwardly until it rests on the bead 2, the latches 5 being retracted or drawn within the peripheral line of the plate 3 in order to allow the latter to be inserted. The latches 5 are then moved outwardly to pass their projecting ends 7 through the apertures 4 in the pail, and this locks the plate in position within the pail. When it is desired to clean the mop the cover members 10, 12 are swung upwardly and the mop head 20 is inserted through the opening 9 and into the basket 25 in the position shown in Figure 1; and then the cover members 10, 12 are closed, so that the handle 21 of the mop projects through the central opening 14. The mop may then be rapidly revolved between the hands and this will cause the head of the mop to beat against the wires of the basket so as to dislodge the dust therefrom and allow it to fall through the basket and collect in the bottom of the pail. While this is taking place, the head of the mop is enclosed and this will prevent the spreading of the dust in the air. After the mop has been cleaned, the covers 10, 12 are opened and the head of the mop is withdrawn, whereupon the covers may be again closed until the device is to be used again. When it is desirable to remove the collected dust from the pail, it is only necessary to move the latches 5 inwardly to unlock the cover plate 3 and the latter, together with the basket, may be lifted from the pail, and the latter may be emptied. If desired, the pail with the plate and basket removed, may be used as an ordinary water pail for various purposes, until such time as it is desired to use the combination for the purpose above described. This device is both simple and convenient and utilizes a pail of ordinary

construction. The hinged covers of the form herein shown, may be very inexpensively blanked from sheet material and the cost of manufacture of the device as a whole is reduced to the minimum.

Having described our invention, what we claim is:

1. A device of the class described comprising a receptacle having an open upper end and formed with an inwardly extending bead adjacent its upper end to form a seat, a plate insertable in the upper end of said receptacle and adapted to rest on said bead, a foraminous basket depending from said plate and extending within said receptacle for the purpose set forth, said plate having an opening over said basket, and movable cover members for closing said opening in said plate.

2. A device of the class described, a receptacle having an upper end and formed with an inwardly extending bead to provide a seat, said receptacle having apertures, a plate insertable in said receptacle to rest on said bead, latch members on said plate adapted to engage in said apertures and in said receptacle to detachably secure the plate to the receptacle, a foraminous basket depending from said plate and extending within said receptacle for the purpose set forth, said plate having an opening over said basket, and movable cover members for closing said opening in said plate.

3. In a device of the character described the combination of a receptacle having an open end, an inwardly extending bead in said receptacle near said open end to form a seat, a flat plate insertable in said open end to rest on said seat, said receptacle having apertures and said plate having latch members insertable in said apertures to secure said plate to said receptacle, said plate having an aperture, a foraminous basket extending from said plate in register with said aperture, and a flat cover composed of a plurality of polygonal sections hinged to said plate and arranged to close the aperture in said plate.

Signed at East Orange, county of Essex, State of New Jersey, the 24th day of January, 1927.

ADOLPH RADO.
ADELAIDE D. W. RADO.
